UNITED STATES PATENT OFFICE

ROGER JEAN ARNOUIL, OF PARIS, FRANCE

HOOD FASTENER

Application filed June 27, 1928, Serial No. 288,768, and in France July 4, 1927.

The present invention relates to an instantaneous attaching device by which two pieces can be either joined together or released. It is chiefly applicable to the rapid closing and 5 opening of motor vehicle hoods.

The said attaching arrangement essentially comprises two elements of which one is secured to one of the pieces to be assembled, for instance the vehicle frame, and the other 10 is secured to the second piece to be assembled, for instance the hood; the said elements fitting into one another in the closing position. Elastic means are disposed between the two 15 elements, in such manner as to effect the blocking or jamming of the said elements, and hence to facilitate the assembling of the two pieces.

Another feature of the invention resides 20 in the fact that one of the said elements carries a strap in which is engaged the second element when the apparatus is closed.

A further feature of the invention resides 25 in the fact that the two elements each carry a plate spring so disposed that in the closing position the two springs are mutually engaged, similar to the meshing of gear teeth, and exercise upon one another an elastic thrust by which the device is held in position.

The following description with reference 30 to the appended drawings, which are given by way of example, shows the manner in which the said invention may be carried into effect.

Figure 1 is a vertical section of two 35 elements of the attaching arrangement, in their separated position.

Figure 2 is a view analogous to Figure 1, but illustrating the closing position.

Figure 3 is a section on the line 3-3 of 40 Figure 2.

Figures 4 and 5 are sectional views of two 45 modifications of the apparatus shown in Figure 2.

Figure 6 is a sectional view of another 50 form of the element secured to the vehicle frame.

Figure 7 is a modification of the apparatus 55 shown in Figure 6 in vertical section on the line 7-7 of Figure 8.

Figure 8 is a sectional view on the line 8-8 of Figure 7.

As observed in Figures 1 to 3, one of the elements *a* consists of a rod or strip which is secured to the vehicle frame at any suitable point, and which carries a plate spring *c* secured at its end *c*₁ to the support *a*. The other element consists of a plate *c* riveted or otherwise secured to the inner face of the hood *r* and attached to a strap *s*. At the 60 upper part of the plate *c* is mounted the end *t*₁ of a plate spring *t*. The two springs *c* and *t* are as shown in the drawing disposed in opposite directions, and have the form of pointed ends or teeth, in such manner that 65 when the element *a* has been engaged in the strap *s* when the hood is lowered, the spring *t* may clear the spring *c*, the two springs remaining in contact and being placed together 70 by their back part and exercising a strong pressure upon one another by which the strap *s* (and hence the hood *r*) is secured to the fixed strip *a*.

As will be observed, the said attaching device can be placed in position in a very simple manner, since it will suffice to lower the hood while placing the strap *s* upon the fixed strip *a*, to obtain the closing or inversely to raise up the hood to obtain the opening.

The two springs *c* and *t* which have the 75 form of pointed ends or teeth, will prevent inadvertent release or improper raising of the hood.

In the form of construction shown in Figure 4, the strap *s* carries a toothed cross-piece *f* engaging the toothed rear face of the rod *a*. The plate spring *c* is compressed by an eccentric or cam *d* pivoted on an axle *l* mounted on the strap *s* and adapted to be placed in tension by a controlling arm *g*.

It will be observed that after lowering the hood in such manner that the strap *s* is placed upon the rod *a*, the members *f* and *a* can be contacted by simply lowering the handle *g*, the pressure thus obtained being an elastic pressure.

In the modification shown in Figure 5, the cross-piece *f* is engaged in one of the notches of the stationary element *a*, and the spring *t* 100

is mounted on the element *q* secured to the hood *r*.

The element or strip *a*, instead of being toothed or notched, may be made with a smooth face, as shown in Figure 6.

The element *a*, instead of being rigidly secured to the vehicle frame, may also be mounted in an elastic manner, as shown in Figures 7 and 8, the elasticity being obtained by a spring *n* which absorbs the vibrations or movements of the hood due to the jarring when on the road, so that the element *a* will be obliged to follow the movements of the hood.

Upon the element *a* may also be mounted rubber buffers *b*, which press upon the hood and prevent all noise.

What I claim is:—

1. In a fastening device for closures the combination of a vertically disposed stationary latch post, a movable loose fitting stirrup formed to be slidably fitted over said latch post, resilient latching means carried by said latch post, and complementary resilient latching means carried by said stirrup said complementary resilient latching means being formed to allow play in a vertical direction whereby strain on the hinges of said fastening device is diminished and simultaneously allow play in a horizontal plane whereby closing and adjustment of said fastening device is facilitated.

2. In a fastening device for the hoods of automobiles the combination of a vertically disposed stationary latch post, a movable loose fitting stirrup formed to be slidably fitted over said latch post carried by said hood, resilient latching means carried by said latch post, and complementary resilient latching means carried by said stirrup, said complementary resilient means having contact surfaces obliquely disposed with respect to said latch post to allow play in the vertical direction whereby strain on the hinges of said hood is diminished and simultaneously allow play in a horizontal plane whereby closing and adjustment of said fastening device is facilitated.

3. In a fastening device for the hoods of automobiles the combination of a vertically disposed stationary latch post, a movable loose fitting stirrup formed to be slidably fitted over said latch post carried by said hood, a curved leaf spring carried by said post having a surface obliquely disposed with respect to said post, and a second leaf spring carried by said stirrup having a surface obliquely disposed with respect to said post and positioned to contact with said first named surface to allow play between said hood and said post in the vertical direction whereby strain on the hinges of said hood is diminished and simultaneously allow play in a horizontal plane whereby closing and

adjustment of said fastening device is facilitated.

In testimony whereof I have signed this specification.

ROGER JEAN ARNOUIL.
